UNITED STATES PATENT OFFICE.

JOHN R. SHEPPARD, OF NEW YORK, N. Y., ASSIGNOR TO THE DENTISTS' SUPPLY COMPANY, A CORPORATION OF NEW YORK.

ARTIFICIAL TOOTH.

1,354,515.

Specification of Letters Patent.

Patented Oct. 5, 1920.

Application filed March 21, 1918. Serial No. 223,711.

To all whom it may concern:

Be it known that I, JOHN R. SHEPPARD, a citizen of the United States, and resident of New York, county of New York, and 5 State of New York, have invented an Improvement in Artificial Teeth, of which the following is a specification.

The object of my invention is to provide an improved construction of artificial tooth 10 facing suitable for bridge, crown, or metal plate work, in which a strong union between the porcelain tooth and the facing back plate may be obtained with a minimum use of platinum.

15 My object is also to provide the tooth facing with an anchor of sheet metal having a fused in part attached to the porcelain and extending therefrom very slightly greater than the thickness of the backing metal 20 plate, and said extension of the anchor shaped to provide end portions which may be flanged over the ends of the slotted opening in the backing plate to hold it to the porcelain preliminary to the union of the 25 anchor and back plate by solder.

By my improved construction, I am enabled to reduce the platinum, heretofore required in corresponding facings, approximately thirty per cent.; and this, when considering the scarcity and very high cost of 30 platinum, is a matter of the utmost importance.

My object is further to simplify the manufacture of the teeth with the anchors attached before applying the backing plates, the advantage being more especially in enabling the mold parts to be provided with a very shallow slot in which to erect the sheet metal pins during the molding of the 40 bisque material, the shallowness of the groove enabling it to be maintained clean and easily cleared of bisque material should any particles thereof find their way into the groove.

45 My invention also consists of improvements hereinafter described whereby the above objects and results are attained, said improvements comprising certain organization and combination of parts which are 50 fully described hereinafter and more particularly defined in the claims.

Referring to the drawings: Figure 1 is a perspective view of a tooth facing embodying my improvements and showing the backing plate ready for application; Fig. 2 is 55 a longitudinal section showing my improved facing with the backing plate secured in place; Fig. 3 is a cross section of the same; Fig. 4 is a sectional view of mold parts showing the manner of supporting the sheet 60 metal anchor in the mold during the molding of the tooth; Fig. 5 is a sectional view similar to Fig. 2, showing a modification of my improved facing; and Fig. 6 is a perspective view of still another modification 65 of the sheet metal anchor forming a part of my invention.

2 is the porcelain facing or tooth proper and may be any of the usual shapes heretofore employed. 3 is the sheet metal anchor 70 structure and is stamped from sheet platinum and molded into the bisque tooth during manufacture, the vitrifying of the tooth forming a strong union between the tooth and anchor. In practice the anchor is held 75 in upright position, Fig. 4 in the lower half 10 of the mold, and extending into the tooth space 14 between the mold parts 10 and 11 and in which the bisque material is packed and molded. In this practice, the wall of 80 the lower mold part 10 is provided with a shallow slot 12 of a depth just sufficient to receive the anchor portion which extends beyond the tooth; and when the end portions of the anchor 2 have the extensions 5 or 5^b 85 the slot is depressed correspondingly at its ends, as at 13, Fig. 4.

The general shape of the sheet metal anchor which is embraced is embedded in the porcelain, may be of any form desired, so 90 long as it secures itself in the porcelain when fused, but the low projecting portions 4 and 5 of the anchor are especially typical of my invention. Referring to Fig. 1, it will be seen that the anchor, for length of 95 the middle part 4, is very slightly extended above the back surface of the tooth and at each end of this middle portion 4 there projects a small extension 5. The backing plate 6 is slotted as at 7 sufficiently to permit the insertion of the parts 4 and 5 of the anchor and then the parts 5, 5, are 100

flanged outward to hold the backing plate firmly in place (Fig. 2). Solder is next applied, as at 9, thoroughly uniting the anchor to the plate. By this construction, it will be seen that there is no large portion of the anchor bent over the backing plate which would interfere with its proper and perfect fitting to the bridge, crown or other plate work to which it must be soldered.

10 My improvements therefore, not only provide a great saving in platinum but insure a relatively smooth or clean back plate, which materially facilitates a perfect fit to the bridge or other work in the mouth.

15 In Fig. 5 I have shown the anchor as formed with a shallow V cut, forming the pointed ends 5^b which are the equivalent of the anchor extensions 5 in Fig. 1, said points being adapted to be flanged over the backing plate 6 in the same manner, the flanging not yet having been done in Fig. 5.

20 In Fig. 6 I have shown a construction of sheet anchor in which the part 4^a between the extension 5 is not cut down as in Fig. 1. In this case the end parts 5 may be flanged over the ends of the slot 7 of the backing plate, and the intermediate portion 4^a pressed down and soldered as before. It will be noted that the end parts 5, 5, are formed by the cuts or slots 5^a, and hence may be flanged over the backing plate as in the case of Fig. 1.

25 I have shown the tooth facing with only a single anchor, by way of example, but it is to be understood that two such anchors may be employed where greater strength is required, as single or double anchors are commonly used in artificial teeth as circumstances may dictate. I therefore, do not 30 restrict myself in this respect.

35 I have also referred to the anchors as formed of sheet platinum, as this metal is the only available metal suitable for the purpose, because it withstands the fusing 40 temperature of the porcelain and also is not injuriously affected by acids and alkalies of the mouth; but I do not confine myself to this particular metal, as my invention would be equally applicable to any alloy of it or other specially prepared metal which may 45 be hereafter found as a satisfactory substitute.

50 It will now be apparent that I have devised a novel and useful construction which embodies the features of advantage enumerated as desirable, and while I have in the present instance shown and described the preferred embodiment thereof which has been found in practice to give satisfactory 55 and reliable results, it is to be understood that I do not restrict myself to the details, as the same are susceptible of modification in various particulars without departing from the spirit or scope of the invention.

60 Having now described my invention what

I claim as new and desire to secure by Letters Patent, is:

1. An artificial tooth facing, comprising a porcelain body having a sheet metal anchor secured therein by the fused porcelain body, 70 and extending slightly from the body throughout its length in a direction parallel to the back of the tooth body, said anchor having a relatively great length as compared to the depth of its longitudinally projecting portion which extends from the back of the tooth body, said depth being very slight and said anchor having at each end a portion projecting to a slightly greater distance from the back of the tooth body to 80 provide widely separated portions adapted to be flanged in opposite directions in the plane of the sheet metal anchor.

2. In an artificial tooth facing, a backing plate, combined with a porcelain body having a sheet metal anchor secured therein by the fused porcelain body and extending slightly from the body throughout its length in an outward direction from the back of said tooth body, the projecting part of said anchor having a relatively great length as compared to its outwardly exposed depth and extending through the backing plate, said outwardly exposed depth of the anchor being very slightly greater than the thickness of the plate and having adjacent each end a portion independently and separately upset or closely flanged over the backing plate to provide mechanical attachment thereto, and said backing plate being of a 100 thickness very slightly less than the depth of the end portions of the anchor before being upset or flanged, and a soldered union between the anchor and backing plate.

3. An anchor for an artificial tooth facing 105 comprising an elongated flat sheet metal body having one of its longest sides shaped to be held in a porcelain tooth and its other longest side provided adjacent its widely separated ends with independent flanging 110 portions adapted to be flanged down independently in the plane of the anchor body, whereby said anchor provides independent flanging portions separated by an intermediate edge portion.

4. An artificial tooth facing, comprising a porcelain tooth body, a backing plate therefor having an elongated slot, a sheet metal anchor fused in the porcelain and extending through the slot of the backing plate 120 to approximately the rear face thereof and having its opposite ends flanged over the ends of the slot in the direction of its length, and the anchor and backing plate securely soldered together.

5. In an artificial tooth facing, a backing plate having a long and narrow slot therein, combined with a porcelain tooth body fitting close to the backing plate and having a sheet metal anchor secured to the fused porcelain 130

- body and extending from the body throughout its length in an outward direction from the back of the tooth, the projecting part of said anchor having a relatively great length 5 as compared to its outwardly projecting depth, the maximum depth thereof very slightly exceeding the thickness of the plate and extending through the aperture of said
- plate and upset so as in effect to be riveted thereto, and the mechanical union so made 10 being further reinforced by the application of solder.

In testimony of which invention, I hereunto set my hand.

JOHN R. SHEPPARD.
